ATTORNEY

UNITED STATES PATENT OFFICE.

CYRUS C. COREY, OF CANADENSIS, PENNSYLVANIA.

STONE-GATHERER.

1,274,244.

Specification of Letters Patent. Patented July 30, 1918.

Application filed March 28, 1917. Serial No. 158,017.

To all whom it may concern:

Be it known that I, CYRUS C. COREY, a citizen of the United States, residing at Canadensis, in the county of Monroe and 5 State of Pennsylvania, have invented certain new and useful Improvements in Stone-Gatherers, of which the following is a specification.

This invention relates to stone gatherers, 10 and aims primarily to provide a simplified and improved machine which, when drawn over the ground, will gather stones and deliver the same to a crushing mechanism, which deposits the crushed stone upon the 15 ground. A further object of the invention is to provide a device of this character which is of light weight so as to be easily operated by draft horses, and which has its mechanism so arranged as to minimize the 20 opportunity for wear or breakage of the various movable parts.

A still further object of the invention is to provide a machine of the character set forth which employs a picker member for 25 lifting stones from the ground, and which is featured by an improved mechanism for adjusting the picker member toward and away from the stone conveyer, whereby the machine may be adjusted to compensate for 30 stones of various sizes. A still further object of the invention is to provide an improved conveyer in connection with a machine of this character, which conveyer includes an improved guard or shield for preventing the stones from being thrown out 35 of the path of the conveyer.

With these objects in view, together with others which will appear as the description proceeds, the invention resides in the novel 40 formation, combination, and arrangement of parts, all as will be described more fully hereinafter, illustrated in the drawings, and particularly pointed out in the claims.

In the drawings:—

45 Figure 1 is a side elevation of a stone gatherer and crusher constructed in accordance with the invention;

Fig. 2 is a top plan view of the machine;

Fig. 3 is an enlarged sectional view taken 50 through the crushing mechanism;

Fig. 4 is a detail view of the picker member and the means for operating the same;

Fig. 5 is a detail fragmentary view illustrating the adjusting means for the picker 55 member; and

Fig. 6 is a detail sectional view taken through the conveyer.

Referring now to the drawings, 10 indicates the frame of a conventional form of vehicle or draft apparatus, and upon which 60 the improved gathering, conveying, and crushing apparatus is located. It is preferred that this frame be of light weight, and yet possess sufficient strength to withstand the strains and pressures to which it 65 will be subjected in use. The frame is mounted upon front and rear wheels 11 and 12 respectively.

The mechanism employed in carrying out the invention includes a hopper 13 located 70 preferably at the forward end of the frame, and within this hopper is pivoted a crushing plate 14. This plate is provided upon its rear face with a laterally disposed roller 15, which is contacted by a cam or oval 75 roller 16. As the cam is rotated through its supporting shaft 17, the crushing plate 14 is forced toward the forward wall 18 of the hopper, and any stones or clods which may be positioned between the wall and 80 plate will be crushed or disintegrated and the crushed portions may escape through the bottom of the hopper as is obvious. The shaft 17 is equipped with a drive wheel 19, over which a belt 20 passes; the said 85 belt being trained over a drive wheel 21 mounted upon the shaft 22 of a suitable power source, such as an internal combustion engine indicated at 23.

Associated with the crushing mechanism 90 above described is a conveyer for moving the stones from the ground into the open upper end of the hopper. A conveyer frame is indicated at 25, and is supported by suitable brackets 26 at its upper end. This 95 frame extends rearwardly and downwardly from the open end of the hopper, and terminates at its rearmost end adjacent the ground. The rear end of the conveyer is suspended from the frame of the vehicle by 100 contractile springs 27. Shafts 28 and 29 are rotatably mounted at the upper and lower ends relatively of the conveyer frame, and these shafts carry sprockets 30, over which belt chains 31 pass. These belt or conveyer 105 chains may be equipped with slats or holding boards 32 to support the stones carried by the conveyer in their upward movement. Carried by the conveyer frame and extending across the same directly beneath the 110

uppermost portion of the conveyer chain is a screen 33, which supports the stones in their upward travel. The screen may be of any desired mesh, depending upon the size stones it is desired to crush. Such as are deposited upon the screen and are small enough to pass through the screen will, of course, be deposited upon the ground, and will not be presented to the crushing mechanism.

10 The extremities of the shaft 29 at the rear end of the conveyer are equipped with wheels or rollers 35, which contact the ground and support the rear end of the conveyer. The shaft 28 is equipped with a 15 sprocket wheel 36, over which passes a chain 37 in driving connection with the shaft 22 of the engine.

10 To prevent the stones delivered to the conveyer being thrown too violently upon the conveyer by the picker element to be hereafter detailed, a shield or guard 40 is employed. This guard extends transversely of the conveyer, and is supported upon the 25 conveyer frame by depending legs 41. Bolts 42 are passed through these legs 41 and through suitable apertures 43 arranged in spaced relation on the conveyer frame. It will be observed that the lower edge of the 30 body portion of the guard is spaced above the conveyer a distance sufficient to permit of the stones carried by the conveyer passing freely thereunder. By providing a guard of this character, it is obvious that 35 stones violently thrown upwardly upon the conveyer will be arrested upon the conveyer. Destruction or disorder of the mechanism or any of the parts by the picker mechanism is thus obviated. By rendering the guard 40 adjustable longitudinally of the conveyer frame, it is apparent that the guard is capable of compensating for different speeds of rotation of the picker member.

The picker member is indicated generally 45 at 50, and includes a rotatable member mounted upon a suitable shaft 51. This rotatable member carries a plurality of arcuate tines or teeth 52, which are adapted to engage the ground and lift stones and clods 50 therefrom. The shaft 51 which carries this picker member is journaled in straps or brackets 53, the said brackets depending from the medial portions of supporting rods 54. The brackets 53 are equipped with 55 spaced openings 55, through any of which a bolt 56 may be inserted to rigidly secure the brackets to the supporting rods. The forward end of each rod is pivoted as at 57 to the adjacent longitudinal bar of the frame 60 10, so that the rods are capable of swinging vertically. Adjusting openings 58 are arranged in spaced relation upon the rods 54 at the forward end thereof, so that the degree of vertical adjustment of the said rods 65 may be regulated. The rear ends of the rods

54 are connected to the lower ends of arms 59 carried by a shaft 60 extending laterally across the vehicle frame. A lever 61 is secured to the shaft 60 for operating the same, and may be equipped with a suitable 70 latch for playing over a segment 62'. It is obvious from this construction, that adjustment of the lever 61 will cause the lowest or middle portions of the rods 54 to move toward or away from the ground, accordingly as the lever 61 is moved. It is also obvious that the supporting brackets 53 may be adjusted upon the rods 54, so that the picker element may be adjusted toward and away from the ground.

75 The brackets 53 support a jack shaft 65, which is equipped at one end with a sprocket wheel 66 over which a power chain 62 is passed. This power chain is also passed over a sprocket upon the shaft 22 of the engine. The jack shaft 65 carries gears 70, which mesh with gears 71 on the picker shaft, so that rotary movement developed in the jack shaft 65 will be transmitted to the picker member.

80 From the foregoing, it is obvious that as the machine is drawn over the ground and the engine 23 is operated, stones will be gathered by the picker member and delivered to the conveyer. The conveyer moves 90 the stones upwardly and into the open end of the hopper, whereupon the latter operates upon the stones to crush and thoroughly disintegrate the same. I have illustrated a hook 75 at the forward end of the machine, 100 and it is intended that a harrow or other ground agitator be secured thereto for loosening the ground prior to picking operation. The various parts of the machine are so assembled as to minimize the opportunity for 105 wear or breakage. The seat for the operator is located preferably at the rear of the machine, and in a position to permit of the operator having ready access to the control lever 61. When it is desired to have the 110 picker member operate upon stones of unusual size, the lever 61 will be actuated so as to move the picker member away from the lower end of the conveyer.

115 While the present is a disclosure of what I believe to be the preferred embodiment of the invention, it is to be understood that the invention is not limited thereto, but that various changes may be made in the construction, arrangement, and proportion of 120 parts, without departing from the spirit of the invention, as defined in the appended claims.

What is claimed is:—

1. In a device of the class described, a 125 vehicle, a conveyer on said vehicle, wheels supporting one end of said conveyer, a picker member adjacent the wheeled end of said conveyer, the said picker member being capable of being adjusted toward or away 130

from said conveyer, and means for adjusting said picker member.

2. In a device of the class described, a vehicle, a conveyer on said vehicle, supporting bars pivoted at one end to said vehicle and being disposed at their medial portions adjacent said conveyer, a lever for adjusting said bars, straps adjustably mounted upon the medial portions of said bars, a shaft rotatably mounted in said straps, a picker roller rotatably supported in said straps, means for transmitting power from said shaft to said roller, and means for driving said shaft.

15 3. In a device of the class described, a vehicle, a conveyer on said vehicle, a guard

adjustably mounted over said conveyer, a picker member for delivering matter to said conveyer, and means for driving said picker member.

20

4. In a device of the class described, a vehicle, a conveyer frame on said vehicle, a conveyer on said frame, a guard adjustably mounted on said frame, and a picker member for delivering matter to said conveyer.

25

In testimony whereof I affix my signature in presence of two witnesses.

CYRUS C. COREY.
